FASTENING-INSERTING MACHINE

Harold Lane and William Neil Bray, Leicester, England, assignors to United Shoe Machinery Corporation, Paterson, N. J., a corporation of New Jersey

Application December 28, 1937, Serial No. 182,111
In Great Britain February 3, 1937

15 Claims. (Cl. 1—20)

This invention relates to fastening-inserting machines and is herein illustrated as applied to a machine of the type disclosed in Letters Patent of the United States No. 1,815,295, granted 5 on July 21, 1931, upon an application of George Goddu, having means for driving staples to fasten shoe uppers in lasted position. It is to be understood, however, that the invention is not limited to machines of that particular type nor 10 to machines for fastening shoe uppers.

Machines constructed as shown in the above-mentioned Letters Patent comprise in their organization means for forming staples and for driving them from a guiding nozzle through shoe 15 upper materials and into an insole, and a deflector for engaging the legs of each staple to curve different portions of the legs successively in the driving operation before the different respective portions enter the shoe and thus to cause 20 them to follow curved paths such as to anchor them effectively in the insole without necessarily penetrating entirely through the latter. Since the upper materials are sometimes thicker at one portion of the shoe than at other portions, 25 and since the insole may be thicker in the shank portion than at the forepart, such machines are provided with means for relatively adjusting the nozzle and deflector to vary the degree or radius 30 of curvature of the staple legs to meet these different conditions, in order that the staple legs will be anchored in the most effective manner in the insole, this means comprising an eccentric controlling the deflector and an adjusting member movable by the operator to turn the eccentric 35 quickly to different predetermined positions corresponding to the desired curvatures of the staple legs in different portions of the shoe. This variation in the thickness of the upper materials or of the insole renders it desirable also that the 40 lengths of the staples be varied, so that staple legs of suitable length for the best results in comparatively thick portions of the work will not emerge from the surface of the work into which they were driven when their curvature is made more pronounced for use in thinner portions of the work. Any such emergence of the 45 staple legs may interfere with subsequent operations on the shoe such, for example, as an upper margin trimming operation or the positioning 50 of an outsole on the bottom of the shoe.

An object of the present invention is to provide means for effecting the above-mentioned variation in the lengths of the staples. In machines of the illustrated type, the staple-forming 55 means comprises an outside former and an in-

side former movable relatively to the outside former to form a staple from fastening material, preferably wire, fed into position to be operated upon. The wire is fed through a guiding nozzle and the extent of its feeding movement, in the 5 construction herein shown, is limited by engagement of an abutment with the free end of the wire. Cooperating with the wire-guiding nozzle to sever the wire is a severing member, the severing member and abutment, for purposes of the 10 present invention, being carried by a pair of slides that are connected together for equal movements in opposite directions to adjust the severing member and abutment relatively to each other and to the inside former to vary the lengths 15 of the portions of fastening material severed to form the staples. In the illustrated construction the slides are controlled by the above-mentioned adjusting member for turning the eccentric which controls the deflector, through a threaded 20 rotatable member connected to one of the slides and to which the eccentric is frictionally clamped, the construction accordingly being such that movement of the adjusting member to turn the eccentric and thereby vary the curvature 25 imparted to the staple legs effects a corresponding variation in the lengths of the legs by movement of the slides to vary the lengths of the portions of fastening material severed to form the staples. Preferably, in order that the 30 legs of each staple when formed will be of equal lengths, the connections between the above-mentioned slides are so constructed as to permit the slides to be adjusted independently of each other relatively to the staple-forming means, 35 and as illustrated also there is provided novel means for maintaining the wire-guiding nozzle in cooperating relation to the severing member in all positions of adjustment of the severing member.

The above and other features of the invention, including novel means for preventing bending of the staples in a direction away from the work in the driving operation and various novel details of construction and combinations of parts, 45 will now be more particularly described with reference to the accompanying drawings and pointed out in the claims.

In the drawings,

Fig. 1 is a view in right-hand side elevation 50 of a portion of the head of the machine in which the invention is embodied;

Fig. 2 is a view partly in plan and partly in section on the line II—II of Fig. 1;

Fig. 3 is a section on the line III—III of Fig. 1;

Fig. 4 is a section on the line IV—IV of Fig. 1; Fig. 5 is a section of certain parts on the line V—V of Fig. 1; and

Fig. 6 is a perspective view of the staple deflecting member.

In view of the disclosure in the above-mentioned Letters Patent of details of the construction of the machine to which the invention is herein shown as applied, only such parts as it is necessary to refer to for an understanding of the invention will be described in detail. It will be understood that a machine of this type is provided with a gripper (not herein shown) which pulls the upper in different locations along the edge of the shoe bottom as the operator presents the shoe in positions determined by a sole rest 10 and a side gage 12. In time relation to the pulling of the upper in each location a staple is driven from a guiding nozzle 14 by a driver 16 to fasten the upper to the insole. As the staple is driven its legs are engaged by a deflector 18 the lower end of which is positioned opposite to the outlet end of the nozzle 14, the deflector acting to curve different portions of the legs successively before the different respective portions enter the shoe to cause the legs to follow curved paths such as to anchor them effectively in the insole without necessarily penetrating through the insole to the interior of the shoe. The driver 16, the deflector 18 and other parts associated therewith are carried by a slide 20 mounted on a guiding member 22 for forward movement in a downwardly inclined path in predetermined time relation to each upper pulling operation. The slide 20 is moved forwardly to carry the nozzle 14 and other parts associated therewith inwardly over the shoe bottom to lay the margin of the upper over the insole, whereupon the staple is driven and the slide 20 is then retracted to its starting position.

As also disclosed in the previously mentioned Letters Patent the deflector 18 is mounted on a pivot pin 24 for turning movement to vary the distance between the portion thereof that engages the legs of the staple and the points where the legs emerge from the end of the staple nozzle 14 and thus to vary the degree or radius of curvature imparted to the legs in the driving operation. The position of the deflector is determined by an eccentric 26 which, in the construction herein shown, is formed on a sleeve 28 (Fig. 3) having a split bearing portion 30 frictionally clamped by means of a screw 32 to a shaft 34 which is carried by the slide 20 and is mounted for turning movement to adjust the eccentric. The eccentric 26 (Fig. 1) bears on a rearwardly and upwardly extending arm 35 formed on the deflector 18 and thus limits movement of the deflector about the axis of the pin 24 in the direction to increase the distance between its lower end and the outlet end of the nozzle 14 and accordingly to increase the radius of curvature of the staple legs. It will be understood that the arm 35 is forced against the eccentric by reason of the pressure applied to the deflector in the staple-driving operation and there is sufficient friction tending to prevent the deflector from turning about its axis to cause it to maintain any position determined by the eccentric.

The shaft 34 in the construction herein shown has a portion 36 threaded into a bracket 38 which is secured to the slide 20. For turning the shaft 34 and the eccentric 26 to vary the position of the deflector 18 in such manner as to alter the curvature of the staple legs in operating upon different

portions of the same shoe, there is provided a device or member 40 having a split bearing portion 42 frictionally clamped to the shaft 34 by a screw 44. Formed as a part of the member 40 is a handle 46 for use in turning the member and the shaft 34. For determining different positions of the member 40 it carries a spring-pressed latch 48 arranged to enter a notch 50 formed in the edge face of an arc-shaped plate 52, this notch serving as a stop to limit movement of the member 40 in one direction, and adjustably secured in a curved guideway 54 in the plate 52 is a stop 56 for limiting movement of the member in the opposite direction. The plate 52 is adjustably secured to a bracket 58 fastened by screws 60 to the slide 20 by means of a clamp, including a wing nut 62, in engagement with a curved surface 64 on the bracket 58 concentric with the axis of the shaft 34. It will be evident that by adjusting the plate 52 relatively to the bracket 58 the notch 50 and the stop 56 may be displaced about the axis of the shaft 34 without affecting their relation to each other to cause the differently curved staples used at different portions of the same shoe to have either a smaller or greater degree of curvature without altering the relation between their curvatures. In order that the radius of curvature of the staple legs may be varied as desired in operating, for example, along the shank portion of the shoe from the heel breast line to the ball line, there are provided in an edge face of the plate 52 a plurality of notches 66. The latch 48 and the notches 50 and 66 are so formed that the latch will slip out of any one of the notches in response to pressure applied by the operator's hand to the handle 46 so that the operator can move the member 40 instantly from one predetermined position to another.

For purposes of this invention the illustrated machine is provided with means controlled by the deflector-adjusting means for varying the lengths of the pieces of fastening material severed and consequently the lengths of the staples formed. As shown, particularly in Figs. 1, 3 and 4, there is formed on the shaft 34 a circular flange 68 which extends into a slot 70 formed in a member 72 slidably mounted for movements in directions laterally of the machine in a guideway 74 formed in the guide member 22. The slot 70 in the member 72 is parallel to the path of movement of the slide 20 and the member 72 is of such length that in the forward and rearward movements of the slide 20 the flange 68 is not moved out of engagement with the member 72. Formed on the member 72 is a stop face 76 (Figs. 2 and 4) against which the end of the staple wire, from which the staples are formed, is fed by feed rolls (not herein shown) which are operated by mechanism substantially like that fully disclosed in U. S. Letters Patent No. 1,796,451, granted on March 17, 1931, upon an application of George Goddu, one of the feed rolls having a smooth wire engaging face to permit it to slip on the wire as the end of the wire engages the stop face 76. Formed in the forward end of the guiding member 22 is a guideway 78 for a slide 80 having secured to it by means of a screw 82 a plate 84 (Figs. 2 and 4) which serves as a shearing member for severing from a length of 70 staple wire a section of the proper length for a staple. Cooperating with the shearing member is a wire-guiding nozzle 86 carried by a block 88 slidably mounted in a guideway 90 in the bracket 38 secured to the slide 20. The block 88 is held 75

in the guideway 90 by a cover plate 92 (Figs. 2 and 3) on which there is formed a lug 94 engaged by one end of a spring 96 seated in a recess in the block 88, the spring 96 tending to urge the block in the direction to hold its inner face 97 (Figs. 2 and 4), which is substantially in the plane of the outlet end of the guiding nozzle 86, in engagement with the shearing plate 84. The guideway 78 of the slide 80 is closed by a cover plate 98 (Fig. 1) which is secured to the member 22 by bolts 100 and is shaped at its right-hand end to provide an outside former 102 for forming the staples. Cooperating with the outside former is an inside former 104 fastened as hereinbefore to the bracket 38 on the slide 20. Supported by the guiding member 22 and extending upwardly at right angles to the directions of movement of the slides 72 and 80 is a stud 106 (Fig. 2) on which there is pivotally mounted a lever 108 having oppositely extending arms 110, 112 of equal lengths. Formed on the ends of the arms 110, 112 are gear teeth 114, 116 meshing respectively with rack teeth 118, 120 formed respectively on the slide 80 and on a pin 122 adjustable lengthwise of the slide 72 in a central bore 124 formed in the slide, a binding screw 126 extending through a slot 128 in the slide being provided for holding the pin in adjusted position.

When the slide 20 is in its retracted position as illustrated in Fig. 1 the wire is fed from the nozzle 86 through guiding slots 129 in the opposite sides of the outside former 102 until its end engages the stop face 76 on the slide 72. In the forward movement of the slide 20 the block 88 is moved forwardly, the nozzle 86 being positioned in such close relation to the shearing plate 84 as to cause the fed-in portion of wire to be severed in response to such movement. Thereafter the portion of wire severed by the shearing member 84 and the nozzle 86 is engaged by the inside former and forced into the outside former to form a staple. It will be evident that after loosening the binding screw 126 the slide 80 may be moved toward or from the path of the inside former 104 to position the shearing edge of the member 84 the same distance from that path as the stop face 76 on the slide 72 to insure that the legs of the staple when formed will be of equal lengths. As the shearing member 84 is thus adjusted the pin 122 through the lever 108 is moved lengthwise in the bore 124 relatively to the slide 72, after which the shearing member 84 and the slide 80 are locked in adjusted position by tightening the binding screw 126. It will be evident also that as the member 40 is turned from one predetermined position to another to vary the position of the deflector 18, the shaft 34 is turned with the member 40 and by reason of its threaded engagement with the bracket 38 receives also a bodily movement laterally of the machine. Since the circular flange 68 on the shaft 34 engages the slide 72 at the opposite sides of the slot 70 the slide 72 is moved with the shaft 34 in the same direction, thus varying the position of the stop face 76 relatively to the inside former. As the slide 72 is thus moved the slide 80, through the pin 122 and lever 108, receives a movement of equal extent in the opposite direction to position the shearing member 84 the same distance from the inside former as the stop face 76. The construction is such that the shearing member 84 and the stop face 76 are moved toward each other in response to counter-

clockwise movement of the shaft 34 (Fig. 1) and are moved away from each other in response to clockwise movement of the shaft 34. As the shearing member 84 and the stop face 76 are thus moved toward or from each other to vary the length of the fastening material severed, the spring 96 acts on the block 88 to hold it in engagement with the shearing member so that the wire-guiding nozzle 86 is at all times in position to cooperate with the shearing member to sever the wire in the forward movement of the slide 20. Preferably the shearing member is constructed so that it may be adjusted relatively to its slide 80 to present a fresh portion of its shearing edge in position to sever the wire when another portion of the shearing edge has become worn.

From the above description it will be evident that the positions of the shearing member 84 and the stop face 76 to vary the lengths of the fastening material severed to form the staples are controlled by the mechanism for relatively adjusting the deflector 18 and nozzle 14 to vary the curvature of the staple legs. It will be understood that with the parts in the position shown in Fig. 1, the latch 48 being in engagement with the notch 50, the shearing member 84 and the stop face 76 are adjusted to cause the shortest piece of wire to be severed and consequently the shortest staple to be formed required for the work in hand, and the eccentric 26 is set to cause the legs of the staple to receive a curvature of comparatively short radius. It will be understood also that the position of the notch 50 may be varied by adjustment of the plate 52 relatively to the bracket 58 to vary the length of the shortest staple required and the radius of curvature imparted to its legs and that the radius of curvature imparted to the staple legs may be still further varied and determined by adjustment of the sleeve 28 about the axis of the shaft 34. Movement of the handle 46 to the right (Fig. 1) to rotate the eccentric in a direction to swing the lower end of the deflector away from the staple nozzle 14 will cause the severing member 84 and the stop face 76 to be moved away from each other an amount determined by the extent of swinging movement imparted to the deflector. Thus, as the deflector is adjusted to cause a curvature of longer radius to be imparted to the staple, a correspondingly longer staple will be formed. In each instance the length of the staple will be such as to permit its legs to be curved in the proper degree to cause it to penetrate the insole to the required depth to fasten the upper and insole securely together without the ends of the staple legs emerging from that face of the work into which the staple has been driven.

In the illustrated machine the position in which the staple is formed is considerably above the position which it occupies at the time when it is driven and it is transferred downwardly from forming position into alignment with the driver 16 by mechanism similar to that disclosed in Letters Patent No. 1,815,295. In order to prevent any possibility of the bar of the staple being bent upwardly in the driving operation by reason of its being unsupported above between the end of the nozzle 14 and the deflector 18, the inside former 104, a portion of which is shown in Fig. 1, has formed on its lower end a projection 130 (Figs. 1 and 5) arranged to extend into a central recess 132 (Figs. 1 and 6) in the deflector, the length of the projection 130 being such that the gap between the outlet end of the staple nozzle 75

14 and the deflector is closed in all positions of adjustment of the deflector.

Having described our invention what we claim as new and desire to secure by Letters Patent of 5 the United States is:

1. In a machine for driving staples into work, the combination with staple-forming means, a driver for driving staples thus formed, a nozzle from which the staples are driven by the driver, and a deflector for engaging the legs of each 10 staple before they enter the work and for curving them as they are driven into the work, of means for effecting a relative adjustment of said nozzle and deflector to vary the curvature imparted to the staple legs, and mechanism movable simultaneously with said adjusting means to effect a corresponding variation in the length of the legs of staples formed by the staple-forming means.
2. In a machine for driving staples into work, the combination with means for forming staples from fastening material fed into position to be operated upon, a driver for driving staples thus formed, and a deflector for engaging the legs of each 15 staple before they enter the work and for curving them as they are driven into the work, of mechanism for determining the limit of feeding movement of the fastening material and for severing from it pieces of different lengths for the 20 operation of said staple-forming means, and means for adjusting said deflector to vary the curvatures imparted to the staple legs and for simultaneously adjusting said mechanism to vary the lengths of the pieces of fastening material severed to form the staples.
3. In a machine for driving staples into work, the combination with staple-forming means, a driver for driving staples thus formed, and a deflector for engaging the legs of each 25 staple before they enter the work and for curving them as they are driven into the work, of mechanism for severing from fastening material pieces of different lengths for the operation of said staple-forming means, a device movable to different 30 predetermined positions for adjusting said mechanism to vary the lengths of the pieces severed, and an eccentric rotatable by the movement of 35 said device for varying the position of said deflector to cause the legs of staples of different 40 lengths to be curved in different degrees.
4. In a machine for driving staples into work, the combination with staple-forming means, a nozzle through which fastening material is fed into position to be operated upon by said staple-forming means, an abutment for engaging the 45 free end of the fastening material to limit the extent of its feeding movement, a member arranged to sever the fed-in portion of fastening material, a driver for driving the staples, and a deflector for engaging the legs of each 50 staple before they enter the work and for curving them as they are driven into the work, of means for 55 adjusting the deflector to vary the curvature imparted to the legs of different staples, and mechanism controlled by said adjusting means for varying the relative positions of the abutment and said severing member to vary the lengths of the portions of fastening material severed to form the different 60 staples.
5. In a machine for driving staples into work, the combination with staple-forming means, a nozzle through which fastening material is fed into position to be operated upon by said staple-forming means, an abutment for engaging the 65 free end of the fastening material to limit the 70

extent of its feeding movement, a device arranged to cooperate with said nozzle to sever the fastening material, a driver for driving the staples, and a deflector for engaging the legs of each 5 staple before they enter the work and for curving them as they are driven, of a member movable to different positions for adjusting the deflector to vary the curvatures imparted to the legs of different staples, and a pair of slides connected to said member and movable thereby to vary the relative positions of said abutment and severing device to vary the lengths of the portions of fastening material severed to form the different 10 staples.

6. A machine for driving staples into work having, in combination, staple-forming means, a nozzle through which fastening material is fed into position to be operated upon by said staple-forming means, a member arranged to sever the fed-in portion of fastening material, an abutment for engaging the free end of the fastening material to limit the extent of its feeding movement, a device movable to different positions for adjusting the deflector to vary the curvatures imparted to the legs of different staples, and a member movable by the operator to adjust 15 said deflector to determine variably for different staples the curvature of the legs and for also controlling said mechanism.

7. A machine for driving staples into work having, in combination, staple-forming means, a nozzle through which fastening material is fed into position to be operated upon by said staple-forming means, an abutment for engaging the free end of the fastening material to limit the extent of its feeding movement, a member arranged to cooperate with said nozzle to sever the fed-in portion of fastening material, said abutment and severing member being adjustable toward or from each other to vary the length of the severed portion of fastening material, a driver for driving the staples, a deflector for engaging the legs of each staple before they enter the work and for curving them as they are driven into the work, a rotatable eccentric for varying the position of said deflector to vary the curvatures imparted to the legs of different staples, and means for rotating the eccentric and for also relatively adjusting the abutment and said severing member to vary the lengths of the portions of fastening material severed to form the different 20 staples.

8. A machine for driving staples into work having, in combination, staple-forming means, a nozzle through which fastening material is fed into position to be operated upon by said forming means, an abutment for engaging the free end of the fastening material to determine the limit of its feeding movement, a member arranged to cooperate with said nozzle to sever the fed-in portion of fastening material, a driver for the staples, a deflector for engaging the legs of each staple before they enter the work and for curving them as they are driven into the work, and means for moving the severing member and said abutment toward or from each other to vary the length of fastening material severed to form the staple and for simultaneously varying the position of the deflector to vary the curvature of the staple legs.

9. In a machine for driving staples into work, 25

the combination with staple-forming means, a driver for driving staples thus formed, and a deflector for engaging the legs of each staple before they enter the work and for curving them as they are driven into the work, of mechanism for severing from fastening material pieces of different lengths for the operation of said staple-forming means, said mechanism comprising a pair of slides connected together for equal movements in opposite directions, an abutment on one of said slides for engaging the free end of the fastening material, a device carried by said other slide for severing the fastening material, a threaded rotatable member for adjusting said slides to determine the length of the piece of fastening material severed to form the staple, and an eccentric rotatable with said said threaded member for adjusting said deflector to determine the degree of curvature imparted to the staple legs.

10. In a machine for driving staples into work, the combination with staple-forming means, a driver for driving staples thus formed, and a deflector for engaging the legs of each staple before they enter the work and for curving them as they are driven into the work, of mechanism for severing from fastening material pieces of different lengths for the operation of said staple-forming means, said mechanism comprising a pair of slides connected together for equal movements in opposite directions, an abutment on one of said slides for engaging the free end of the fastening material, a device carried by said other slide for severing the fastening material, a threaded rotatable member for adjusting said slides to determine the length of the piece of fastening material severed to form the staple, and an eccentric rotatable with said threaded member for adjusting said deflector to determine the degree of curvature imparted to the staple legs, said eccentric being adjustable relatively to said threaded member to vary the position of the deflector.

11. In a machine for driving staples into work, the combination with staple-forming means, of a member for guiding fastening material fed into position to be operated upon by said staple-forming means, an abutment for engaging the free end of the fastening material to limit the extent of its feeding movement, a device arranged to cooperate with said guiding member to sever the fastening material, means for moving the severing device and said abutment toward or from each other to vary the length of fastening material severed to form a staple, and means for maintaining the guiding member in cooperating relation to said severing device in all positions of adjustment of said device.

12. In a machine for driving staples into work, the combination with staples-forming means, of a member for guiding fastening material fed into

position to be operated upon by said staple-forming means, an abutment for engaging the free end of the fastening material to limit the extent of its feeding movement, a device arranged to cooperate with said guiding member to sever the fastening material, means for moving the severing device and said abutment toward or from each other to vary the length of fastening material severed to form a staple, and a spring for holding the guiding member in a position determined by the position of the severing device.

13. In a machine for driving staples into work, the combination with staple-forming means, a member for guiding fastening material fed into position to be operated upon by said staple-forming means, and a device arranged to cooperate with said guiding member to sever the fed-in portion of fastening material, of an abutment for engaging the free end of the fastening material to limit the extent of its feeding movement, and mechanism for moving said abutment toward or from said staple-forming means and for imparting to said severing device a movement of equal extent in a direction opposite to the direction of movement of said abutment to vary the length of the fastening material severed to form the staple, said mechanism comprising a pair of slides for moving said abutment and device and connections between said slides constructed to permit the slides to be adjusted independently of each other relatively to said staple-forming means.

14. In a machine for driving staples into work, a staple nozzle, a staple driver, a deflector having a deflecting face spaced from the outlet end of said nozzle for engaging the legs of each staple before they enter the work and for curving them as they are driven into the work, an outside former, and an inside former movable relatively to said outside former to form the staples, said inside former having a projection formed thereon extending into the space between the end of the nozzle and said deflecting face to support the bar of the staple against bending away from the work after the bar leaves the nozzle in the driving operation.

15. In a machine for driving staples into work, a staple nozzle, a driver for driving staples from said nozzle, an outside former, an inside former movable relatively to said outside former to form the staples, said inside former having a projection formed thereon extending beyond the outlet end of said nozzle for guiding the bars of the staples in the driving operation after the bars leave the nozzle, and a deflector arranged to engage the legs of each staple before they enter the work and to curve them as they are driven into the work, said deflector having a recess formed therein to receive said projection.

HAROLD LANE.
WILLIAM NEIL BRAY.
